Gregory & Matkin

(57) **CLAIM**

The ornamental design for a simulated live bait fishing lure,
as shown and described.

DESCRIPTION

FIG. 1 is a perspective view of a simulated live bait fishing
lure showing my new design;

FIG. 2 is a top plan view thereof;

FIG. 3 is a bottom plan view thereof;

FIG. 4 is a side elevation view thereof, the opposite side
being substantially a mirror image;

FIG. 5 is a front elevation view thereof;

FIG. 6 is a rear elevation view thereof; and,

FIG. 7 is a sectional view taken substantially along line 7—7
in FIG. 4.

1 Claim, 3 Drawing Sheets
